United States Patent Office.

JAMES C. DUNCAN, OF OLNEY, ILLINOIS.

Letters Patent No. 64,647, dated May 14, 1867.

PLoughs.

The Schedule referred to in these Letters Patent and making part of the same.

TO ALL WHOM IT MAY CONCERN:

Be it known that I, JAMES C. DUNCAN, of Olney, in the county of Richland, and State of Illinois, have invented a new and useful improvement in Ploughs; and I do hereby declare the following to be a full, clear, and exact description of the same.

I make a plough consisting of the mould-board, land-side, and a supporting border or sole out of a single piece of metal, the same being cut from slab steel or iron and swaged into form while heated. I have found that by this method of construction great economy of manufacture is attained and a substantial and good article produced.

In order that others skilled in the art to which my invention appertains may be enabled to fully understand and use the same, I will proceed to describe it in detail.

In Figure 1 of the drawings the plough is represented as attached to the beam G, handles M M', &c.

In Figure 2 is represented what may be termed the plough-blank, the same being cut out of slab steel or iron, and having a diamond shape or trapezoidal form, an incision being made through the blank for about half its length from the heel toward the point so as to enable the metal to be swaged or bent to form the mould-board A and land-side B. The mould-board and land-side are thus permanently united at the forward part of the plough, and both terminate at a common point which may be made to serve the purpose of a share. In bending the blank into shape while under heat the lower edge of the land-side B is formed with an inwardly-projecting horizontal border or sole, C, which is intended to afford a good sliding surface, and also to keep the plough steady in operation. The heel-brace D is also formed in one piece with the mould-board and land-side, and is bent so as to form a horizontal support or rest, D', for the plough-beam G, as represented in fig. 1. The rest D' may be slotted, as seen in Figure 4, to receive the bolt P, which fastens the beam thereto, and this slot enables the beam to be adjusted so as to take more or less land. The plough thus constructed is adapted for the attachment of the handles by means of bolts or otherwise, and may be braced by a bolted cross-piece at E, Figure 3, and attached to the beam G by means of the sheth F and rod H. Instead of attaching the handle M' to the mould-board by a separate screw-bolt, the extremity of the heel-brace may be inserted through the handle and mould-board and riveted on the outside. This plough may be made light or heavy, according as it is designed for a cultivating or breaking plough, and it may be used singly or in gang. I, Figures 1 and 5, is a bar having a salient cutting edge, i, and fastened to the land-side by bolts or otherwise. In operation the cutting edge i divides the rod and facilitates the work of the plough. A beard may be cut on the land-side of the point of the plough for the purpose of shielding the forward extremity of the bar I, or a separate piece, J, may be attached for this purpose.

Having thus described my invention, what I claim as new, and desire to secure by Letters Patent, is—

1. A plough embracing the mould-board A, land-side B, border or sole, C, and heel-brace D, all being united in one and the same piece of metal, which is cut and shaped substantially as described and represented.
2. I claim the slotted rest D', when formed in one piece with the plough and employed for the support of the beam G, substantially as and for the purpose specified.
